UNITED STATES PATENT OFFICE.

JOHN HALTERBECK, OF NEW YORK, N. Y., ASSIGNOR TO GOTTERIED PIEL, OF NEW YORK, N. Y.

ABRADING-MACHINE.

1,212,213.

Specification of Letters Patent. Patented Jan. 16, 1917.

Application filed September 4, 1912, Serial No. 718,546. Renewed June 8, 1916. Serial No. 102,602.

To all whom it may concern:

Be it known that I, JOHN HALTERBECK, a subject of the Emperor of Germany, and a resident of New York city, borough of Bronx, in the county of New York and State of New York, have invented certain new and useful Improvements in Abrading-Machines, of which the following is a specification.

10 This invention relates to abrading machines, more particularly to machines in which the abrading member consists of an endless traveling belt of emery cloth, sand paper or the like.

15 The principal object of this invention is to provide in an abrading machine of this character, guiding and supporting means for the work whereby curved surfaces of any given radius of curvature may be cut, 20 ground or finished to any desired depth.

25 Another object of this invention is to provide guiding and supporting means for the work whereby conical as well as cylindrical surfaces of any desired curvature and depth may be cut.

30 A further object is to provide in a machine of this character, means whereby both flat and curved surfaces of any degree of curvature may be cut.

35 A still further object is to provide in a machine of this character, means for automatically withdrawing the dust caused by the abrasion of the material.

The various other objects will appear 35 from the detailed description and will be particularly pointed out in the claims.

In carrying out my invention, I mount a 40 guide plate on either side of the small roller, one of which plates is adjustable so as to form a varying angle with the other plate. When

45 it is desired to cut, grind or finish a curved surface on a piece of material, the edges of the surfaces are guided on the guide plates and the portion of the work between these edges is hollowed to a depth depending upon the degree of angularity of the guide plates with respect to each other. The table for holding the work is also tiltable to permit the grinding of a conical surface of any

50 desired curvature and depth. For grinding upon the same band, flat surfaces and likewise surfaces requiring irregular or shallow curvature, two additional tiltable tables are provided, one adjacent a stationary support 55 situated behind the emery cloth and the

other adjacent the drum by which the emery cloth is driven. To avoid the accumulation of dust, a brush is applied to the emery cloth and an exhaust flue is disposed adjacent thereto for drawing away the dust dislodged by the brush.

In the accompanying drawings:—Figure 1 is a plan of my invention, the work being illustrated in dot and dash lines to indicate how it is guided while having a cylindrical surface cut therein. Fig. 2 is an elevation of the machine, the dot and dash lines adjacent the small roller indicate the position of the table and work when set to cut a conical surface. Figs. 3 and 4 are diagrams illustrating the effect of varying the angle between the guide plates.

Power is transmitted from any convenient source through a belt 1, passing under idler pulleys 2 to a drive pulley 3 connected to a drum 4 over which passes an endless band of emery cloth or sand paper 5. The latter passes over roller 6, driven from the drum shaft through suitable gearing 7 and 8, and then passes under the tightening roll 9 and around the small roll 10 and roll 11 and returns to the drum 4. The tightening roll is adjusted in any suitable manner as by a hand wheel 9^a clamping a slotted lug 9^b extending from a pivoted arm 9^c on which the roller 9 is mounted.

Adjacent to the roll 10 is mounted a tiltable table 12 pivotally mounted on a stand 13 fixed to the frame work. Table 12 has wings 14 and 15 extending on either side of the roller, and between these wings and the runs of the belt of emery, cloth or sand paper are mounted preferably vertical plates 16 and 17. Plate 16 is stationary while plate 17 is adjustable so as to vary the angle formed between it and plate 16. The adjusting means for plate 17 consists preferably of an arcuate segment 18 projecting from the plate having an arcuate slot 19 through which passes a stud bolt 20 projecting from standard 21. The segment may be clamped to the standard in adjusted position by a suitable thumb nut 22 on the stud.

The work 23 indicated in dot and dash lines in Fig. 1, engages the plates 16 and 17 at two points 24 which determine the radius of curvature of the curved surface. When it is desired to increase the depth of the hollowed out portion with a given radius 110

of curvature the angle between plates 16 and 17 is decreased. Referring to the diagram in Fig. 3, line $a-b$ is the chord of the arc $a-c-b$ the altitude of which is $c-d$. When the difference between the grinding points is increased to $x-y$, the altitude $c-z$ of the arc $x-c-y$ has the same proportion to the chord $x-y$ as the altitude $b-c$ has to the chord $a-b$. The relative depth of the hollow or depression remains unchanged. In Fig. 4 the angle between plates 16 and 17 is decreased and the distance between points a^1-b^1 has been kept the same as the distance $a-b$ in Fig. 3. It will be noted that with the same length of chord the altitude 15 of arc $a^1-c^1-b^1$ is considerably greater than altitude $c-d$ in Fig. 3. The relative portion of arc with reference to the circumference of the circle has been increased, thus producing a steeper depression or hollowed out portion in the work than is produced with the adjustment of plates 16 and 17 in Fig. 3.

To abrade or grind a flat surface, a tiltable table 25 is provided adjacent the run of the belt of emery cloth between drum 4 and roll 11. Behind this run of belt a flat vertical stationary plate 26 is provided to maintain the emery cloth flat while the work is pressed against it. For abrading surface of irregular or shallow curvature a tilttable 30 table 27 is provided adjacent drum 4.

For removing or disposing of the dust produced by the abrasion of the work a brush 28 is preferably mounted at a convenient point to bear against the emery cloth. This brush may be mounted on plate 16 and adjacent to the same a flue 29 may be provided through which the dust may be sucked by an exhaust fan or vacuum cleaning device 35 or any other suitable means. The guide plates 16 and 17 act also as dust guards and coöperate with the exhausting device to keep the dust away from the operator.

It will thus be clear that with the construction above described a cylindrical or conical surface of any desired radius of curvature or depth may be cut or ground on the work. When it is desired to make a 45 deeper cut of the same radius of curvature the adjustable guide plate is adjusted to reduce the angle between it and the stationary plate, whereas, if it is desired to increase the radius of curvature without changing the 50 depth of cut the adjustable plate is adjusted to increase the angle between it and the stationary plate and at the same time the distance between the guiding points on the work is increased. It will also be noted that 55 by the above described machine flat surfaces and surfaces of irregular or shallow or convex curvature may be also cut on the same band which is used for cutting the cylindrical or conical surfaces. Thus a variety of 60 shapes and forms may be finished on the 65

same machine, avoiding the necessity of taking one object to several machines if it has several differently shaped surfaces.

Various changes may be resorted to within the skill of the mechanic without departing from the spirit and scope of the invention as defined in the claims.

Having thus described my invention, I claim:

1. In an abrading machine for concave surfaces, an abrading member for engaging the concave surface as the member and surface are moved relatively, a rigid guide placed on either side thereof at an angle to each other for engaging edges of the surface during the relative movement, said guides being spaced away from the path of the concave surface, means for adjusting the angle between the guides, and means for supporting the work to be held in engagement with the guides and the abrading member.

2. In an abrading machine for concave surfaces, an abrading member comprising a traveling belt for engaging the surface as the belt and surface are moved relatively, a guide having a flat bearing surface placed on either side thereof at an angle to each other for engaging edges of the surface during the relative movement, said guides being spaced away from the path of the concave surface, means for adjusting the angle between the guides, and means for supporting the work to be held in engagement with the flat bearing surfaces of the guides and the abrading member.

3. In an abrading machine for concave surfaces, an abrading member for engaging the concave surface as the member and surface are moved relatively, a guide placed on either side thereof at an angle to each other for engaging edges of the surface during the relative movement, said guides being spaced away from the path of the concave surface, means for adjusting the angle between the guides, and a tilttable table for supporting the work to be held in engagement with the guides and the abrading member.

4. In an abrading machine for concave surfaces, an abrading member comprising a traveling belt for engaging the surface as the belt and surface are moved relatively, a guide placed on either side thereof at an angle to each other for engaging edges of the surface during the relative movement, said guides being spaced away from the path of the concave surface, means for adjusting the angle between the guides, and a tilttable table for supporting the work to be held in engagement with the guides and the abrading member.

5. In an abrading machine for concave surfaces, a vertical roll, an abrading band passing thereover for engaging the concave surface as the surface and band are moved

- relatively, a pair of vertical guide plates on either side of the roll, placed at an angle to each other for engaging edges of the surface during the relative movement, said 5 guide plates being spaced away from the path of the concave surface, means for adjusting the angle of the guide plates, and a table mounted adjacent said plates adapted to support the work against said roll and 10 guide plates, the angle between the table and the guide plates being free of obstruction whereby work of any size or shape may be disposed in said angle.
6. In an abrading machine for concave 15 surfaces, a vertical roll, an abrading band passing thereover for engaging the concave surface as the surface and band are moved relatively, a pair of vertical guide plates one on either side of the roll, placed at an angle 20 to each other for engaging edges of the surface during the relative movement, said guide plates being spaced away from the path of the concave surface, means for adjusting the angle of the guide plates, and a 25 table mounted adjacent said plates adapted to support the work against said roll and guide plates, said table having wings extending closely adjacent to said guide plates.
7. In an abrading machine for concave 30 surfaces, a roll, an abrading member passing thereover for engaging the concave surface as the member and surface are moved relatively, a pair of guide plates for the work mounted one on each side of the roll for engaging edges of the surface during the relative movement, said guide plates being spaced away from the path of the concave surface, a brush on one of said plates engaging the abrading member, and a table 35 adjacent the guide plates, said guides constituting also dust shields.
8. In an abrading machine for concave 40 surfaces, a vertical roll, an abrading band passing thereover for engaging the concave surface as the surface and band are moved relatively, a pair of vertical guide plates one on either side of the roll for engaging edges of the surface during the relative movement, said guide plates being spaced away from 45 the path of the concave surface, placed at an angle to each other, means for adjusting the angle of one of the guide plates, said adjusting means comprising a segment attached to one of the plates, and means for 50 clamping the segment to a stationary part of the frame.
9. In an abrading machine for concave 55 surfaces, a vertical roll, an abrading band passing thereover for engaging the concave surface as the surface and band are moved relatively, a pair of vertical guide plates one on either side of the roll, placed at an angle 60
- to each other for engaging edges of the surface during the relative movement, said guide plates being spaced away from the 65 path of the concave surface, means for adjusting the angle of one of the guide plates, said adjusting means comprising a slotted arcuate segment attached to one of the plates, a stationary stud extending through 70 said slot, and means for clamping the segment to the stud.
10. In a machine for abrading concave 75 surfaces, an abrading member having a surface adapted to enter the concavity and to engage the surface thereof as the member and concave surface are moved relatively, and a guide for engaging an edge of the concave surface during the said relative movement, said guide being spaced from the 80 path of the concave surface, the portion of the guide engaging said edges being immovable relative to each other.
11. In a machine for abrading concave 85 surfaces, an abrading member adapted to enter the concavity and to engage the surface thereof as the member and surface are moved relatively, and guides one at each side of the member for engaging edges of the 90 surface during the relative movement, said guides being spaced from the path of the concave surface and each having a substantially straight bearing surface.
12. In a machine for abrading concave 95 surfaces, an abrading member adapted to enter the concavity and to engage the surface thereof as the member and surface are moved relatively, and a guide for engaging an edge of the surface during the relative movement said guide being spaced from the 100 path of the concave surface, and adjusting means for revolving said guide about a point exteriorly of the same to change the direction of the guide.
13. In a machine for abrading concave 105 surfaces, an abrading member adapted to enter the concavity and to engage the surface thereof as the member and surface are moved relatively, guides one at each side of the member for engaging edges of the 110 surface during the relative movement, said guides being spaced from the path of the concave surface, and adjusting means for changing the angle between the guides, the apex of said angle being a fixed point positioned between the members.

Signed at New York city, in the county of New York and State of New York, this 30th day of August, 1912.

JOHN HALTERBECK.
